UNITED STATES PATENT OFFICE

FRANK A. HATFIELD, OF LOS ANGELES, CALIFORNIA, ASSIGNOR OF FIFTY-ONE PER CENT TO WALDO H. LOGAN AND FORTY-NINE PER CENT TO EDSON R. WOLCOTT, BOTH OF LOS ANGELES, CALIFORNIA

APPARATUS FOR PUMPING LIQUIDS

Application filed May 22, 1928. Serial No. 279,631.

This invention relates to apparatus for pumping liquids and particularly to an apparatus of the general type described in patent to Edson R. Wolcott, No. 1,628,943, for pumping liquids through considerable vertical heights, as in pumping oil or other liquid from wells of relatively great depth. While the apparatus described in said patent and the improvements thereof comprising the present invention are particularly adapted for the pumping of oil from oil wells, the same may also be advantageously used for pumping other liquids.

The pumping apparatus described in said patent comprises an outer casing or pipe extending throughout the height of the apparatus, partitions at suitable intervals dividing the interior of said casing into a plurality of pump chambers or stages located contiguously one above another, passage means for conducting liquid from the lower portion of each pump chamber to the next higher chamber and provided with check valve means for permitting only upward flow of liquid therethrough, two gas passage means extending substantially throughout the height of the pump and communicating respectively with the upper portions of alternate pump chambers, and means for maintaining relatively high and low pressures in the respective gas passage means and for periodically reversing the relation between the pressures therein.

It will be seen that with such an arrangement, liquid is continually displaced from each chamber communicating with the gas passage in which relatively high pressure exists to the next higher chamber, which is in communication with the gas passage in which relatively low pressure exists. When the conditions of pressure in the respective gas passages are reversed, each chamber which was filled with liquid in the preceding period is emptied into a still higher chamber, and so on throughout the height of the pump. Liquid is drawn, or permitted to flow, into the lowermost pump chamber through suitable inlet means provided with a check valve during each period of relatively low pressure therein, and is discharged from

the uppermost pump chamber through suitable outlet means also provided with a check valve during each period of relatively high pressure therein.

The principal object of the present invention is to provide an advantageous embodiment of the above elements, in such manner that the apparatus may be assembled and lowered into a well, or raised from a well and dismantled, with the greatest convenience and facility, and that a maximum quantity of liquid may be handled in an apparatus of given total outside cross-sectional dimensions.

A particular object of the invention is to provide novel means for maintaining a liquid-tight division between the successive pump chambers and between the several passage means and the pump chambers, and thus effectively prevent leakage of liquid being pumped, or of the working fluid (usually gas or air), from one chamber to another or between any of said passages and pump chambers.

In the apparatus which I have invented to accomplish the above objects, the outer casing is formed as a cylindrical pipe consisting of sections secured together by collar members in the usual manner of well casing or tubing; the successive liquid-conducting passages are combined in a single cylindrical pipe also consisting of sections similarly secured together, and extending within said outer pipe and provided with opening means adjacent the bottom of each pump chamber establishing communication with the pump chambers and with upwardly opening check valves just above the respective opening means; and the two gas passage means are also formed as cylindrical pipes consisting of sections similarly secured together, and extending within said outer pipe and each provided with opening means adjacent the upper ends of alternate pump chambers establishing communication with said chambers; while the partitions between the several pump chambers are formed by partition plates extending transversely of the outer pipe and secured between adjacent sections thereof at suitable intervals, said partition plates having openings through which the

100

three inner pipes pass and being provided with gasket means which are pressed tightly in position to provide a liquid-tight fit between the partition plates and the inner and outer pipes. The spaces inside the outer pipe and around the three inner pipes, and between successive partition plates, constitute the several pump chambers.

A particular feature of the invention consists in the shape of gasket means provided for insuring a liquid-tight fit between the partition plates and the inner pipes, and the manner in which the same are compressed into position upon connection of the adjoining sections of outer pipe, so as to be clamped tightly around the inner pipes and thus prevent relative movement of the inner pipes with respect to the partition. The prevention of such relative movement is essential to the maintenance of the necessary liquid-tight fit at these points. To provide this liquid-tight connection, each of the partition means between adjacent pump chambers comprises two partition plates adapted to fit within the outer pipe or within a suitable coupling member secured thereto and provided with openings to receive the inner pipes, and such plates are provided with bevelled seats around said openings on the adjacent faces of the plates. Gasket rings, formed, for example, of suitable soft metal such as lead or copper, are provided, fitting closely around the respective inner pipes and within the spaces provided by the bevelled seats on said plates. Said gaskets are also bevelled or tapered to conform to the general direction of the bevelled seats on the partition plates, being thicker at their middle portions and tapering inwardly toward the respective pipes at each end, but the tapered faces of said gasket rings are preferably inclined at a somewhat less angle to the axes of the respective pipes than the bevelled seats on the partition plates, in order to provide a certain wedging action of the partition plates on the gasket rings as hereinafter described. Shoulder means are provided on suitable clamping members secured to the outer pipe, adapted to engage said partition plates and force the same together upon tightening of said clamping members, and thus press the gasket rings tightly into position around the respective inner pipes.

The accompanying drawings illustrate my invention and the type of pumping apparatus to which it is intended to be applied, and referring thereto:

Fig. 1 is a diagrammatic vertical section of the upper portion of a pumping apparatus such as shown in the above mentioned patent of Edson R. Wolcott and to which the improvements of the present invention are applicable.

Fig. 2 is a similar view of the lower portion of such pumping apparatus.

Fig. 3 is a side elevation partly broken away, of one stage of such pumping apparatus.

Fig. 4 is a vertical section through the adjoining ends of two adjacent stages of the pump and the connecting and partition means therebetween, taken on line 4-4 in Fig. 6.

Fig. 5 is a similar view on line 5-5 in Fig. 6.

Fig. 6 is a horizontal section on line 6-6 in Fig. 4.

Fig. 7 is an enlarged section on line 7-7 in Fig. 6, showing the partition plates and gasket means in the positions they occupy before the partition plates are squeezed together to press the gasket means into tight engagement with one of the inner pipes.

Fig. 8 is a similar view showing the gasket means pressed into final position by squeezing the partition plates together.

Referring to Figs. 1 and 2, the pumping apparatus comprises essentially an outer casing 1 extending throughout the height thereof and partition means 2 at suitable intervals dividing the space within said casing into a plurality of pump chambers or stages 3 located contiguously one above another, passage means 4 for conducting liquid from the lower portion of each pump chamber to the next higher pump chamber, check valve means 5 located in the respective liquid conducting passages and preferably at or near the bottom thereof and adapted to permit only upward flow of liquid therethrough, and two gas passage means 7 and 8 extending substantially throughout the height of the pump and provided at suitable points with openings placing the respective gas passage means in communication with alternate pump chamber. For example, the gas passage means 7 is shown as provided with openings 9 communicating with the upper portion of the uppermost stage, the third stage down, and so on throughout the length of the apparatus, while the gas passage means 8 is provided with openings 10 communicating with the second stage and with every alternate stage from there on down. In Fig. 2 the gas passage means 8 is shown as opening at its lower end as at 10', directly into the lowermost pump chamber, while the gas passage means 7 is shown as opening at its lower end as at 9', directly into the next higher pump chamber.

Beneath the lowermost stage is provided any suitable length of casing 1' having openings or perforations 11 for inflow of liquid thereto, and a liquid conducting passage 4' may extend down inside said casing and be provided with check valve 5' at its lower end, so that liquid may be forced up therethrough into the lowermost pump chamber 3 during the low pressure interval therein.

The liquid conducting passage means 4" leading from the uppermost pump chamber

may be connected to a pipe 12 for conducting away the liquid delivered therethrough, while passage means 7 and 8 may be connected through suitable manually or automatically controlled valve means to sources of relatively high and relatively low pressures, whereby a condition of relatively high pressure and relatively low pressure may be alternately created in the respective gas passages and hence in the pump chamber connected thereto. Such means for creating high and low pressure in the gas passages and for controlling the duration of each period of high pressure and low pressure in the respective passages may be substantially the same as shown in the above mentioned patent, or any other suitable means, including, for example, any form of properly timed reciprocating or rotating valve, may be employed for this purpose. The valve mechanism may be operated by electric motor, or by a gas operated motor driven, for example, by a portion of the same gas as is used for the pumping operation.

In order to obtain maximum utilization of the available space within the well, and provide for the maximum size of working chambers and gas and liquid passages, the liquid passage means 4 and gas passage means 7 and 8 are preferably disposed inside the outer casing 1 so that the pump chambers are provided by the spaces inside said casing and around and between said passage means. In practice some difficulty has been experienced in assembling the outer casing and the several passage means therein and at the same time providing the necessary partition means 2 between the several pump chambers, in such manner as to prevent leakage between the respective passage means and the pump chambers, between the exterior of the casing and the pump chambers, and between successive pump chambers, and one of the main objects of the present invention is to provide a simple means for overcoming these difficulties.

While in Figs. 1 and 2 the passage means 4, 7 and 8 are shown as arranged substantially in a single plane, this is merely for the purpose of diagrammatic illustration, and in practice it is much more advantageous to arrange the passage means in a triangular relation to one another as shown in the remaining figures of the drawings. It will also be understood that the height of each stage or pump chamber is much greater than represented in proportion to the diameters of the casing and passage means, and this fact is indicated in Figs. 1 and 2 by breaking away intermediate portions of each stage. Each stage or pump chamber normally extends throughout a height of several hundred feet and as it is impracticable to use individual sections of such great height, each stage, such as indicated at A in Fig. 3, is made up by connecting together a plurality of sections

of inner and outer pipes. The outer casing or pipe 1 of each stage may thus consist of a plurality of pipe sections 101 secured together by standard coupling or collar means 50, and the respective inner pipes or tubes 50, and the respective inner pipes or tubes 104, 107, and 108 in each stage, secured together by standard coupling or collar means 51, 52, and 53.

Referring now more particularly to Figs. 4 to 8 inclusive I will describe the means for securing together the end pipe sections of adjacent stages of the pumping apparatus and for securing the partition and gasket means in position. The standard tubing collar 13, which in the usual oil well pump tubing is normally threaded on to the upper end of each section of tubing, is removed from such normal position and threaded on to the lower end of the pipe section 101 which is to be connected to the pipe then in the well. A special clamping collar 14, having an inwardly projecting shoulder 15, is then screwed on to the upper end of the pipe section 101', which is the top pipe section then in position in the well. The inner pipes 4, 7 and 8, or sections 104', 107' and 108' thereof, are understood to be already in position within the outer pipe section 101', with their upper ends projecting above the upper end of such outer pipe section sufficiently to receive the partition plates and gasket means as hereinafter described.

A gasket ring 17 is then preferably placed on shoulder 15, then the lower partition plate 18, gasket rings 19, 20 and 21, and upper partition plate 22 are placed on top of gasket ring 17 and around the respective inner pipes, the partition plates and gasket rings being at this time approximately in the positions indicated for gasket ring 19 in Fig. 7. The partition plates 18 and 22 are both provided with openings 35 of sufficient size to permit the same to be slipped over the several pipe sections 104', 107' and 108' while fitting fairly closely around the same and are also provided with bevelled seats 27 around said openings and adjacent the upper face of partition plate 18 and the lower face of partition plate 22. The gasket rings 19, 20 and 21 are of such diameter as to fit closely around the pipe sections 104', 107' and 108' respectively and are also bevelled or tapered on their outer faces to conform to the general direction of the bevelled seats on the partition plates, being thicker at their middle portions and tapering inwardly toward the respective pipes at each end. However, as shown in Fig. 7 the tapered faces of said gasket rings are preferably inclined at a somewhat less angle to the axis of the respective pipes than are the bevelled seats on the partition plates. A special clamping nipple 24 having its lower end formed as a shoulder or abutment means 25 is then screwed down inside the collar 14 so

190

105

110

115

120

125

130

as to squeeze the partition plates 18 and 22 together between the clamping member 24 and the shoulder 15 on the clamping member 14, and press the gasket rings tightly into position around the respective inner pipes as shown in Fig. 8.

Referring to Figs. 7 and 8 it will be seen that due to the less inclination of the gasket rings than of the bevelled faces 27 of the 10 partition plates, said gasket rings are first engaged by the partition plates at their respective extremities and a wedging action is thus exerted thereon which forces the metal of said gasket rings into extremely tight engagement with the walls of the inner pipes and tends to force such metal into the small 15 spaces between the pipes and the partition plates, and thus positively insures a tight fit at these points. The downward pressure of 20 shoulder 25 against the partition plates not only serves to compress the gasket means 19, 20 and 21 between said plates, but also brings the lower plate 18 down tightly against the gasket ring 17, thus providing a liquid-tight 25 fit at the outer edges of the partition plates.

Additional sections 107" and 108" of the two gas conducting passages may then be secured in position above the partition means. In order to provide communication, however, 30 between the liquid conducting passage 4 and the pump chamber 3, above the partition plates, a short section of perforated tubing 30 is preferably connected between adjacent sections 104" and 104" of such liquid conducting 35 passage, and a special collar 31 provided with check valve 32 is also preferably inserted between perforated tubing 30 and the next higher pipe section 104". Said check valve is adapted to permit upward flow, while 40 preventing downward flow, of liquid in passage 4. The next higher outer pipe section 101", with collar 13 thereon, may then be screwed onto the nipple 24, and the connection between stages is thus completed. It may be 45 pointed out that, in order to facilitate the connection of pipe sections 101", 104", 107" and 108", the outer pipe section 101" is ordinarily brought into position above the piping already in the well, with the several inner 50 pipe sections 104", 107" and 108" supported loosely therein, so that after the inner pipe sections are connected, the outer pipe section may simply be lowered into position.

I claim:

55 1. In apparatus for handling fluids, the combination of an outer pipe, a plurality of inner pipes extending within said outer pipe, two partition plates extending across the interior of said outer pipe and around said inner pipes and having bevelled seats at their adjacent faces and around said inner pipes, tapered gasket rings disposed around the respective inner pipes and within the spaces provided between said bevelled seats and tapering in the same general direction as said

bevelled seats and clamping means on said outer pipe and operable to clamp said partition plates together and compress said gasket means and cause tight engagement thereof with said inner pipes.

2. A construction as set forth in claim 1, the tapered faces of said gasket rings having a smaller inclination with respect to the axes of the several inner pipes than the corresponding bevelled seats on said partition 75 plates.

3. In apparatus for pumping liquids, the combination of an outer casing comprising a plurality of pipe sections secured together end to end, partition means disposed between adjacent pipe sections at suitable intervals and dividing the space within said outer casing into a plurality of pump chambers, two gas conducting pipes extending within said outer casing and substantially throughout the height thereof and provided respectively with opening means establishing communication between said gas conducting pipes and the upper portions of alternate pump chambers, a liquid conducting pipe also extending within said outer casing and substantially throughout the height thereof and having opening means establishing communication between the interior of said liquid conducting pipe and the lower portions of the several pump chambers and check valve means between successive opening means therein and adapted to permit only upward flow of liquid therethrough, said gas and liquid conducting pipes each comprising a plurality of pipe sections secured together end to end, said partition means each comprising two plates extending one above the other entirely across the outer casing and provided with separate openings through which the several gas and liquid conducting pipes pass, gasket means held in position between the two plates of the respective partition means and around the several gas and liquid conducting pipes so as to substantially prevent leakage between adjacent pump chambers, and coupling means connecting together the adjacent pipe sections of the outer casing at opposite sides of the respective partition means and serving to clamp the two plates of said partition means together and squeeze said gasket means tightly around the several gas and liquid conducting pipes.

4. In apparatus for pumping liquids the combination of a vertically elongated outer 120 casing, a continuous liquid conducting pipe and two continuous gas conducting pipes extending within and substantially throughout the height of said outer casing, partition means disposed at suitable intervals throughout the height of said outer casing so as to divide the space inside said outer casing and around said inner pipes into a plurality of pump chambers, each of said partition means comprising two plates disposed one above the 125 130

other and extending across the interior of said outer casing and around said liquid and gas conducting pipes, gasket means held in position between the plates of the respective partition means and around the several inner pipes to prevent leakage between adjacent pump chambers, and coupling means connecting together the portions of the outer casing above and below the respective 5 partition means and serving to clamp the two plates of said partition means together and compress said gasket means tightly around the several inner pipes, said liquid conducting pipe being provided with opening means establishing communication between the interior thereof and the lower portions of the respective pump chambers and with check valve means between successive 10 opening means and permitting only upward flow of liquid therethrough, and the respective gas conducting pipes being provided with opening means establishing communication between the interior thereof and the upper portions of alternate pump chambers. 15 20 25 In testimony whereof I have hereunto subscribed my name this 27th day of April, 1928.

FRANK A. HATFIELD.
